CLAIM

The ornamental design for furniture hardware, as shown and described.

DESCRIPTION

FIG. 1 is an isometric view of furniture hardware showing the design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The shading lines shown in the drawings represent the approximate three-dimensional contour of the claimed design and are not intended to indicate surface decoration. The broken lines shown in the drawings illustrate portions of the furniture hardware that form no part of the claimed design.
